UNITED STATES PATENT OFFICE.

EMMETT E. WEISER, OF INDIANAPOLIS, INDIANA.

DESIGN FOR A BREAD-GRATER.

SPECIFICATION forming part of Design No. 32,672, dated May 15, 1900.

Application filed February 19, 1900. Serial No. 5,857. Term of patent 7 years.

To all whom it may concern:

Be it known that I, EMMETT E. WEISER, a citizen of the United States, residing at Indianapolis, in the county of Marion and State 5 of Indiana, have invented and produced a new and original Design for Bread-Graters; and I do declare the following to be a full, clear, and exact description of the same, reference being had to the accompanying drawings, forming a part thereof.

This invention relates to a new and original design for a bread-grater; and the object is to provide a design of this character that shall be both useful and ornamental.

15 Referring to the drawings, Figure 1 is a perspective view of a bread-grater, showing my new design; Fig. 2, a transverse sectional view; Fig. 3, a fragmentary plan view, and Fig. 4 a fragmentary detail view.

20 The leading feature of the design resides in a rectangular oblong frame with vertically-disposed sides A A and shorter sides or ends B B and a grating-plate D, arranged within the frame, so as to have a concave surface 25 from which the grating-teeth E rise. Disposed in spaces between opposing sets of teeth are circular sifting-perforations F. The grating-plate D is attached at its longer edges to the longer sides A A of the frame at about 30 the lines a a or somewhat above the center of the frame, while the center b of the trough-like plate is depressed somewhat below the sides thereof, d designating the bottom of the

frame. The grating-teeth and sifting-aper- 35 tures of said grating-plate are arranged sub-stantially as shown in plan in Fig. 3—that is, the teeth and the perforations are in the same lines, as 1 1, 2 2, 3 3, or 4 4, the imaginary lines being parallel. In each line are perforations, as at 5 and 8, between which are two 40 sets of teeth, as at 6 and 7, and so on throughout the line 1 1. The next adjacent line, as 2 2, is identically arranged; but each adja- 45 cent pair of teeth sets, as 9 and 10, is disposed so that the space between coincides with the transverse lines on which the circular aper- 50 tures are placed, and so on alternately throughout the plate, the distinguishing feature of this design for grating-plate being that each circular aperture F appears to be surrounded by six groups of grating-teeth, each group be- 55 ing at the sides of a triangular aperture, and each triangle having a point directed toward the circular aperture. One end B of the frame has a handle C; but this is a subordi- nate feature of my design.

Having thus described my invention, what I claim is—

The design for a bread-grater as herein shown and described.

In testimony whereof I affix my signature in presence of two witnesses.

EMMETT E. WEISER.
